DRAINAGE BAG

William N. Daniels, New York, N. Y.

Application February 17, 1940, Serial No. 319,407

8 Claims. (Cl. 128—283)

My invention relates to bags for use by persons having undergone certain surgical operations which require the use of a receptacle to receive excretions discharged from the body of the wearer.

After an operation of ileostomy or colostomy, such a bag or belt is generally used by the afflicted person.

The bags or belts heretofore used for the purpose above stated have not proved satisfactory to the wearer, many of them being unsanitary, hard to keep clean, uncomfortable and often painful to the wearer.

Having undergone such an operation, I tried for many months to find a suitable bag for my use but could find none, either in the hospital supply department or in places dealing in such supplies.

After much study and experimenting I learned that the dimensions of the bag must be determined, the material used must be flexible and waterproof, durable and easily cleaned, and the device so fitted to the body of a wearer that it may be worn in comfort whether walking or resting in an inclined position.

The object of my invention is to provide a drainage bag construction for the purposes stated which may be made at a low cost and which will be of proper form and dimensions, with flexible means for securing the bag to the body of a wearer in a proper manner to permit easy adjustment in securing the bag to the body, and to maintain the bag in a distended condition and in fluid tight relation with the body of the wearer.

A further object is to provide a bag of the character described, with a removable inner lining of waterproof material to directly receive the excretions from the body of a wearer, which thereafter may be removed from the outer bag together with its contents, without removing the outer bag from the body, and a new bag inserted for further use.

Some further objects of my invention will be hereinafter set forth.

Referring to the drawing which forms a part of the specifications:

Fig. 1 is a perspective view of a bag construction embodying my invention, disclosing the inner or contact side of the bag which rests against the body of the wearer, together with the inner lining receptacle which is removable therefrom.

Figs. 2 and 3 show a vertical section thru the middle of the bag and lining receptacle, and the

cap for the bag shown in Fig. 2, and made to fit over the top in fluid tight relation.

Fig. 4 is an elevational view of a supporting member which fits in the upper end of the bag in freely removable relation and is vertically adjustable therein, and serves to maintain the proper spaced opening between the inner walls of the bag and inner receptacle.

Fig. 5 is a plan view of the construction shown in Fig. 4.

Fig. 6 is a perspective view of the inner receptacle, formed to fit easily into the outer bag and conforming to the shape thereof in the form of a lining.

The bag 10 is preferably made of soft rubber 15 or Neoprene, or other suitable material that is waterproof and will permit of thorough cleaning repeatedly without serious deterioration.

The seams are reinforced in the usual manner to insure strength, and the upper edge portion 20 10' is thickened to increase its strength and to better support the cap 11 which fits thereover in fluidtight relation.

The near side of the bag is formed with a circular opening 12 the edge of which is heavily beaded by thickening the material as illustrated at 12'.

The measurements of the bag should be approximately as follows:

5 inches wide, about 8 inches long, and the 30 opening across about 1½ inches, and the circular opening about 2 inches in diameter for the colostomy which projects into the bag when properly adjusted.

13 indicates a nonrustable thin resilient metal 35 brace formed substantially as illustrated, and comprising a resilient wire 14, the ends of which are hook shaped and are attached to the brace in detachable relation, said wire resting just below the opening 12 of the bag.

On the outer side of the bag a loop 15 is formed integral with the bag, and extends from about ½ inch below the top rim downwardly for about 2 inches, and an elastic belt 16 is passed thru the loop and is adjustable relative thereto, and its ends are secured by a buckle of nonrustable material, or other suitable means, not shown.

The distance between the inturned edges 13' is about 3 inches.

The inner receptacle 17 may be made of waterproof paper or thin oil-cloth that is strong enough for the required purpose, and may be discarded after its original use together with its contents, this arrangement being sanitary as well as avoiding many difficulties heretofore ex- 55

perienced in the use of bags as formerly provided.

The receptacle 17 is formed to provide an extension 17' which extends below the opening 12 as illustrated, and also an upper flap portion 18 over which the cap flanges extend and clamp it to the bag to prevent sagging of the receptacle and to serve as a handle in removing the receptacle from the bag.

- 10 It will be observed that the construction as a whole is more or less elastic and that when strapped to the body of a wearer, it may be worn without undue pressure on the body while maintaining a fluid tight relation therewith; 15 that all odors are suppressed; that the device takes up very little space; and that it may be worn with comfort.

In making the bag I prefer to make the lower ends curved in form to avoid sharp corners and 20 to prevent the lodgment of excretions therein, the form of said corner portions being shown as indicated at 19.

It will be understood that the bag may be used 25 without the inner receptacle in the event that one is not available at the time required.

It will also be understood that minor changes 30 in the form of the bag and of the inner receptacle may be made, and also the brace construction may be altered so long as it is made to serve the functions of distending the upper end of the bag and is formed to provide an opening thru which excreta may pass in a proper manner.

In removing the inner receptacle from the bag, 35 the belt is stretched enough to relieve the pressure on the tab end 17' and the cap 11 removed from the top, after which the flap portion 18 may be grasped and the receptacle easily removed from the bag, as will be readily understood.

While I have described the brace as being 40 made of metal, it may be made of any suitable material that will serve the functions of a distending brace that is resilient and that will stand scalding water and chemical action required to keep it in a sanitary condition.

45 Having thus described my invention I claim as new:

1. A device of the character described comprising a flexible waterproof bag, open at its upper end and formed to provide two oppositely disposed flat side portions in one of which is an opening located near the upper end thereof and adapted to receive a colostomy, a band-like brace located in the upper end of the bag and separating said side portions a predetermined distance apart, a cap for closing the upper end of said bag and which extends around the upper end of said brace, and a belt for supporting said bag on the body of a wearer.

2. A device of the character described comprising a flexible bag open at its upper end and formed to provide two oppositely disposed flat side portions in one of which is an opening located near the upper end thereof and adapted to receive a colostomy, a brace located in the upper end of the bag and separating said side portions a predetermined distance apart, a cap for closing the upper end of said bag, a belt for supporting said bag on the body of a wearer, and a receptacle of waterproof material located in said bag and forming a lining for a predetermined portion thereof, and freely removable from said bag through said upper opening when said cap is removed therefrom.

3. A device of the character described comprising a flexible bag open at its upper end and

formed to provide two oppositely disposed flat side portions in one of which is an opening located near the upper end thereof and adapted to receive a colostomy, a brace located in the upper end of the bag and separating said side portions a predetermined distance apart, a cap for closing the upper end of said bag, an elastic belt for supporting said bag on the body of a wearer, and a receptacle of waterproof material located in said bag and forming a lining for a predetermined portion thereof, and freely removable from said bag through said upper opening when said cap is removed therefrom, whereby said receptacle may be removed from said bag without removing said bag and belt from the body of the wearer. 15

4. A device of the character described comprising a flexible bag, open at its upper end and formed to provide two oppositely disposed flat side portions in one of which is an opening located near the upper end thereof and adapted to receive a colostomy, a bandlike brace located in the upper end of the bag and separating said side portions a predetermined distance apart, a cap for closing the upper end of said bag and which extends around the upper end of said brace, 20 a belt adapted to support said bag on the body of a wearer, said bandlike brace being formed to provide two end portions which extend toward each other and terminate adjacent said side opening in the bag, and a wire extending from the lower end of one of said end portions to the opposite lower end portion and normally resting below said opening.

5. A device of the character described comprising a flexible bag, open at its upper end formed to 35 provide two oppositely disposed flat side portions in one of which is an opening located near the upper end thereof, means in closing said upper end, a band-like brace located in the upper end of said bag serving to separate said side portions 40 a predetermined distance apart, and a receptacle of waterproof material forming a lining for said bag and a part of which hangs freely thru said side opening and covers the lower edge and marginal portions thereof. 45

6. A device of the character described comprising a flexible bag, open at its upper end and formed to provide two oppositely disposed flat side portions, in one of which is an opening located near the upper end thereof, a band-like brace located in the upper end of the bag and serving to separate said side portions a predetermined distance apart, an external cap for closing the upper end of said bag and which extends around the upper part of said brace, a belt for holding 55 said bag against the body of a wearer, and a receptacle of waterproof material forming a lining for said bag, a part of which hangs freely thru said side opening and covers the lower edge and marginal portion thereof and is held in 60 position by the pressure of said bag against the body of said wearer by said belt, and a part of which extends over the upper end of said bag and is held in place by said cap, whereby said receptacle is removable from said bag through said 65 upper opening when said cap is removed and the pressure of said belt is partially released, without removing said bag and belt.

7. A device as defined in claim 6, in which said receptacle extends from the top to the bottom 70 of said bag.

8. A device as defined in claim 6, in which said brace is flexible and said external cap is flexible and elastic.
